(57) **CLAIM**

The ornamental design for a tripod, as shown and described.

DESCRIPTION

FIG. 1 is a perspective view of a tripod showing my new design where the tripod is in a first configuration of use; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a perspective view of the tripod where the tripod is in a second configuration of use; FIG. 10 is a perspective view of the tripod where the tripod is in a first folded state; FIG. 11 is a perspective view of the tripod where the tripod is in a second folded state; FIG. 12 is an enlarged view of portion 12 shown in FIG. 1; FIG. 13 is an enlarged view of portion 13 shown in FIG. 1; and, FIG. 14 is an enlarged view of portion 14 shown in FIG. 1. The dash-dash broken lines in the drawings depict portions of the tripod that form no part of the claimed design. The dot-dash broken lines represent boundaries of the enlarged portions and form no part of the claimed design.
